UNITED STATES PATENT OFFICE.

ARTHUR WELLS MINNEY, OF STOCKTON, CALIFORNIA, ASSIGNOR OF ONE-HALF TO
F. L. BOYD, OF STOCKTON, CALIFORNIA.

CAR-WHEEL BOXING AND OILING DEVICE.

Application filed March 28, 1921. Serial No. 456,858.

To all whom it may concern:

Be it known that I, ARTHUR WELLS MINNEY, a citizen of the United States, and a resident of Stockton, in the county of San Joaquin and State of California, have invented certain new and useful Improvements in Car-Wheel Boxing and Oiling Devices, of which the following is a specification.

10 This invention is an improved car wheel boxing and oiling device for use in connection with railroad rolling stock, the object thereof being to provide a novel, simple and efficient structure of bearing for receiving 15 the journaled ends of the axles with which the wheels are generally formed, and the connection therewith of an oiling or lubricating device for conveniently lubricating the bearings in order to avoid excessive heating 20 or burning out of the bearings, thereby preventing wrecks due to hot boxes and serving to facilitate getting the traffic over the road.

A further object of the invention is to 25 provide a novel lubricating device which causes a continuous circulation of the oil, thereby resulting in a saving of oil, to filter the oil each time it is used during such continuous circulating in the lubricating process, thereby preventing hot boxes as 30 stated, causing the train to run easier and smoother and resulting in a considerable saving in expense for oiling or lubricating purposes, as regards the journal boxes of the rolling stock.

35 Other and further objects of my invention will become readily apparent to persons skilled in the art, from a consideration of the following description when taken in conjunction with the accompanying drawings, 40 wherein:

Figure 1 is a vertical longitudinal sectional view through an oiling or lubricating device constructed in accordance with the invention.

45 Figure 2 is a perspective view of a bearing employed in connection with the device, and which checks the wear.

Figure 3 is a perspective view of a part of the oiling device.

50 Figure 4 is a perspective view of the oil collecting disk forming a part of the oiling device, and

55 Figure 5 is a perspective view of a plate used in connection with the bearings and which fits on part of the bearing between

the bearing and the top of the boxes to hold the bearing down on the journal.

Referring to the drawings in detail, in which like reference characters designate corresponding parts throughout the several views, the numeral 10 designates the journal box through the apertured rear wall 11 of which the journal end 12 of the car wheel axle is adapted to extend, said aperture being designated at 13 and being sufficiently large to admit the entrance of a head 14 at the end of the journal or spindle end of the axle, and in the form of an annular flange or circumscribing shoulder as shown. The inner portion of the journal box is in the form of a rectangular casing or housing including the rear wall or inner wall 11, bottom and sides and a closed top portion provided at its juncture with the vertical wall 15 of the vertically disposed front portion of the box 75 with a transverse shoulder 16 for a purpose to be subsequently specified. The outer end of the boxing is enlarged vertically and laterally to provide an oil reservoir having a depending portion or reservoir proper 17 extending below the bottom portion of the journal box proper designated at 10 thus providing means for containing a good supply of lubricating oil in said reservoir or well. It should be noted that the inner wall 80 of the reservoir 17 is offset outwardly with respect to the wall thus providing means at the top for accommodating an oil collecting or distributing device for feeding oil to the bearing and the journal as will be herein-after pointed out. The front of the box is designated at 19 and the top at 20 which in conjunction with the side walls 21 are provided with an inclined opening covered by 85 a closure 22 having the suitable apertured or other form of handle 23 at the lower end thereof whereby it may be opened on its hinges or pivot 24 by which it is connected to the sides and top of the box. The pivot 90 is preferably in the form of a bolt extending through lugs or apertured ears at the opposite sides of the box, the top being recessed to accommodate the projecting end of the lid or cover 22 as indicated at 25. In order to secure the lid in a closed position, there is mounted on the top 20 a spring 26 which is secured on a top 27 mounted on the top 20 through the medium of a bolt 28 engaged through apertures in their respective parts 95 as clearly shown in Figure 1 of the drawings.

100

105

110

The spring is normally tensioned downwardly as shown, thereby holding the lid closed, while the lid is provided near its pivoted end and at its outer face with a recess 29 to receive the curved free end of the spring, in order to permit the free end of the lid to be opened wide for gaining access to the interior of the box for any purpose. The nut 30 securing the bolt in position is secured to the under side of the top portion 20 and therefore cannot be tampered with. The top face of the box 27 is beveled or tapered so as to incline the spring 26 and thereby facilitate the exertion of pressure to hold the lid closed while still permitting the lid to be readily opened through the medium of the handle 23 projecting from the lower edge thereof.

At the bottom of the box 10 are located a series of transverse vertical partitions or walls 31 having aligned apertures or openings 32, said walls being designed to support a foraminous plate or screen 33 having downturned ends engaged or bent down at its ends against the sides of the end walls or partitions 31, in order to retain the screen in position. The screen is adapted to support the felt 35 and hold the same up against the journaled end 12 and at the inner portion of the boxing. The babbitt or other form of bearing is shown particularly in Figures 1 and 2 and is designated at 36. This bearing is of rectangular form and is provided with a concaved recess 37 in the bottom conforming to the journal end or spindle of the axle, while the opposite sides thereof are beveled throughout its length as indicated at 38. At the inner end there is provided a transverse shoulder or vertical projection 39 and intermediately of the opposite sides, triangular projections or lugs 40 which fit up against ribs 41 on the inside walls of the boxed ends so that the bearings will be had. Near its forward end the top portion of the bearing is provided with a funnel-like oil receiving depression 42 having a central discharge opening 43 to which the side walls incline, while leading from said opening 43 are transverse oil grooves 44 communicating with longitudinally extending oil grooves 45 all on the under side or concaved portion or face of the bushing or babbitt of the bearing and cut into the same, in order that oil discharged through the depression 42 will be fed through the journal or spindle end of the axle for thoroughly and neatly distributing the oil or lubricant thereto. In order to secure the bushing or babbitt of the bearing in position, an angular plate, preferably of right angular formation, as designated at 46 is fitted on top of the bearing so as to engage the top 14 of the boxing, to hold the bearing down on the journal. This plate is provided with an apertured projection 47 in order that the plate may be conveniently

engaged with a suitable object or tool for removing the plate for purposes of renewing the bushing or babbitt of the bearing or otherwise as desired in practice. This operation can be conveniently effected, so as to displace the plate as by turning the same through a suitable arc, in order to disengage the same from behind the projecting shoulder or strap 16, it being understood that certain parts of the lubricating device to be hereinafter described are removed, in order to permit the removal and application of the bushing or babbitt.

The oil collecting and distributing device, in connection with the specific form of bearing and babbitt or bushing, further includes a disk or disk-like rotary oil carrier having a rim 48 having inwardly extending side flanges or circumscribing annular walls 49 providing a channel therebetween. Bolts 50 at the outer face or edge of the disk-like oil carrier carry an axial hub 51 which extends beyond the opposite face a trifle and is secured against the enlargement 14 of the journal or spindle end of the axle. For this purpose, the enlargement 51 is preferably provided with a pair of sockets 52 engaged by bolts or screws 53 passing through similarly spaced axially extending apertures 54 in the hub, the outer face of the hub being provided with a recess or depression 55 accommodating the ends of the bolt or screws so that the disk-like oil carrier is securely held in position on the end of the journal or spindle of the axle whereby it will dip into the oil in the reservoir 17 at the bottom of the enlarged front portion of the box. In this manner the oil will be retained within the walls or flanges of the disk-like oil carrier rim, and will be turned upwardly during the rotation thereof with the axle, as will be later described. This part of the device, specifically, constitutes the oil gathering or collecting means, the oil adhering to the rotating device, that is the inner walls of the rim and the flanges or side walls and being turned around by centrifugal action, cohesion and adhesion.

The oil distributing means comprises a bottom plate or pan 56 having side flanges 57, the outer end of the plate or pan preferably tapering to a point and the inner end being unobstructed, that is the flange or wall 57 being omitted at the inner end in order that oil flowing on or deposited on the plate or pan may readily flow therefrom into the distributing funnel or recess 42 when the parts are positioned as shown in Figure 1 of the drawings. Longitudinally of the bottom plate or pan 56 there is provided a projection or receptacle 58 which fits beneath the inner flange of the pulley, or over which the oil carrier rides in use, the oil carrier by reason of its construction preventing the oil from flying off and carrying oil up to be

scraped off by the scraper 58 from which it flows to subsequently reach the bearings as will be hereinafter more specifically set forth. Extending in alignment with the 5 projection forming the scraper 58 and made fast to or formed integral with the plate 10, is a projection or rib 59 which is raised thereon and which is provided with a horizontal longitudinal slot 60 extending substantially throughout the length thereof but terminating at spaced points from the ends thereof in order that the slots will be confined. Straddling the projection or rib 59 raised on the plate is a post 61, the lower end 10 thereof being grooved or bifurcated as indicated at 62 in order to freely engage over said rib or projection and having a transverse pin 63 extended through the apertured furcations and through the slot 60 in order to allow adjustment of the hanger post along the rib or projection and the necessary angular or pivotal movement to compensate for the movement between the journal and boxing, when the car is jolting up and down, 15 or is taking a turn, so that the journal bearing will shift to one side or the other, as the rim of the disk or oil carrier is down over the ends of the scraper, the scraper will be permitted to stay under the rim of the wheel and not injure the device or parts thereof. In addition, unusual wear will be avoided. The post 61 is provided with a reduced squared or other polygonal shaped cross sectioned reduced portion 64 at the upper end, 20 designed to fit a corresponding opening 65 in the top 20 of the boxing in rear of the oil carrier, this construction preventing the bolts and nuts from turning, while a nut 66 is engaged on the threaded upper end 67 of the hanger bolt, forming a reduced threaded shank therefor, in order to engage the top face of the boxing and retain the distributing device in position. A pin 63 is preferably retained in position through the instrumentality of a key engaging either end thereof and disposed against the opposite faces of the post, although it is to be understood that any other means may be employed for this purpose. Thus, when the car is 25 moving, the oil will be collected and carried upwardly by the oil carrier, and will be scraped off by the distributing device, from which it will flow onto the projection and pan, discharging at the rear end thereof into the funnel or recess 42 and being subsequently distributed to the bearing. As before stated, the recess 62 allows sufficient space for the post to work on the projection 59 and in order to overcome slackage, so that the oiling device will be reliable by retaining the scraper in contact with the inner flange or edge of the disk, an arm 69 is carried by the hanger post extending through the same and anchored by a nut 70 at the inner end thereof against the inner face 30 of the post, while connected to the forward or outer end of the arm is a retractile spring 71 which in turn is connected to the projection or rim 59 as through the medium of an apertured lug or eyelet 72, thus exerting upward tension on the scraper or bottom plate or pan, owing to the fact that the post is rigidly suspended as above described while the plate or pan is pivoted thereto, with sufficient working room between the raised 35 projections or rim 59 of the bifurcation or recess 52. The free end of the arm 69 is suitably apertured for engagement with the upper end of the spring, any suitable construction being provided for this purpose. 40 As the oil is distributed to the bearing, it travels along the grooves 44 and 45 to thoroughly lubricate the journal or spindle end of the axle and will then be absorbed by the felt, so that the latter will be thoroughly supplied with the oil or lubricant and thereby retain the bearing in a cool and thoroughly lubricated condition. The oil after passing through the felt will pass through the foraminous plate or screen 33 and flow 45 down into the bottom of the boxing 10 and through the opening 32, subsequently discharging into the well 17 to be continuously carried up and distributed for lubricating the bearings as heretofore described. Thus, 50 a thorough circulation or continuous feeding and discharging of the oil or lubricant will be insured, so that hot boxes will be prevented, thereby avoiding wrecks, in addition to saving oil and helping to get the 55 traffic over the roads, a sufficient quantity of oil being retained in the well of the boxing to keep the journal thoroughly and properly oiled. In this way, the cost of upkeep and maintenance will be greatly reduced, the oil being continuously filtered on its way back to the reservoir or well for reuse, after having passed through the bearing and then through the felt and screen or filter. The 60 trains will thus run easier and smoother in addition to the labor saving effect caused by the device. The device can be very economically produced and applied, without material alterations, except in the box. It will also be understood that the retaining plate 46 for 65 securing the bushing or babbitt of the bearing in position will engage the shoulder or rim 39 at the inner end of said bushing, thus retaining the plate in position. The bushing also engages the shoulder or end 14 and is thereby retained against outward displacement or end thrust. In this way, the babbitt or bushing of the bearing will not drop into the boxing and it may be stated 70 in general that the device is substantially fool proof. 75 In view of the foregoing, it is thought that the operation of the device will be readily understood and in view of the simplicity and practical value, that it will 80

readily recommend itself to those skilled in the art.

Having thus described my invention what I claim is:—

- 5 1. A lubricator for journal boxes comprising an oil collector mounted on the journal, a scraper adjustably and pivotally mounted on the journal box and cooperable with the collector, yieldable means for holding the scraper in cooperative engagement with the collector, and a distributor coacting with the journal and receiving the oil from the scraper.
- 10 2. The combination with a boxing and a spindle end therein, a bushing fitting the spindle, filter and oil holding means below the spindle, said bushing having an oil opening and grooves at the spindle, a disk hav-

ing a hub attached to the spindle and dipping in oil in the boxing, said disk having a flanged rim receiving oil therein, a post suspended from the top of the boxing, a pan slidably suspended at the lower end of the post for adjustment toward and away from the disk and having a rim adapted to collect and discharge the oil to the opening in the bushing at the rear thereof and having a raised portion forming a scraper disposed within and adapted to engage the rim of the disk, said post being rigid, and spring means carried by the post and engaging the scraper to hold the same outwardly and upwardly against the rim and adapted to permit adjustment of the scraper upon its support.

ARTHUR WELLS MINNEY.
